UNITED STATES PATENT OFFICE.

JOHN C. WINANS AND HARRY KELLEY, OF WALDRON, MICHIGAN.

KEROSENE-VAPORIZER AND GAS-GENERATOR.

1,150,725.

Specification of Letters Patent.

Patented Aug. 17, 1915.

Application filed May 29, 1915. Serial No. 31,168.

To all whom it may concern:

Be it known that we, JOHN C. WINANS and HARRY KELLEY, citizens of the United States, residing at Waldron, in the county 5 of Hillsdale and State of Michigan, have invented certain new and useful Improvements in Kerosene-Vaporizers and Gas-Generators; and we do hereby declare the following to be a full, clear, and exact description 10 of the invention, such as will enable others skilled in the art to which it appertains to make and use the same, reference being had to the accompanying drawings, and to the letters and figures of reference 15 marked thereon, which form a part of this specification.

This invention relates to new and useful improvements in kerosene vaporizers and gas generators and consists of a simple and 20 efficient device of this nature having various details of construction, combinations and arrangements of parts which will be herein-after fully described, shown in the accompanying drawings and then specifically defined in the appended claim.

Our invention is illustrated in the accompanying drawings, in which:

Figure 1 is a central longitudinal sectional view through the device, parts being 30 in elevation. Fig. 2 is a cross sectional view taken on line 2—2 of Fig. 1. Fig. 3 is a top plan view.

Reference now being had to the details of the drawings by letter, A designates a generator, consisting of a pipe having two curved branching portions B with burners C at the ends thereof. A suitable base or air chamber D, of any suitable material, is provided with a longitudinal channel B' 40 upon the bottom of which the said curved portions B rest and the top of such base is recessed away as at E to receive the air and gas mixers H which are positioned over the jets or burners. Flame deflectors K depend 45 from the generator and are positioned immediately over the jets or burners in order to deflect the heat.

It will be noted that the air chamber has a bottom portion N adjustable by means of 50 screws O and that the generator is held to the base by means of a strap K', the ends of

which are angled and held by bolts or other suitable means to the base. A suitable tank T is shown as being provided with a valved outlet T' from which a pipe S leads to a valve S', allowing the oil to pass into the generating chamber. A suitable asbestos wick, designated by letter X, is mounted in the generator chamber, the same being inserted through an opening in the end which 60 is closed by a plug Y.

In operation, the base of the generator is adapted to rest upon the grates in the bottom of a fire box, stove or range. The air, which mixes with the gas, passes through 65 the grates and on through the base or air chamber, thence passing through the mixing devices adjacent to the flames and, when the flame is burning, it will come in contact with the deflectors, thus spreading the flame. 70 In practice, the channel in which the curved pipes rest is preferably filled with asbestos or ashes and a little oil may be poured in the channel or allowed to flow through the gas tips for lighting purposes and, after the 75 apparatus is in operation a short time, sufficient heat will be generated so that the apparatus will produce its own gas.

What we claim to be new is:—

A kerosene vaporizer and gas generator 80 comprising a base which is hollow with apertures in the bottom thereof and a hollow bottom within said generator is adjustably held, the upper surface of the bottom of the base having a longitudinal groove there- 85 in, curved pipes leading through the top of the base and positioned in said groove, the top of the base having a longitudinal groove with openings leading through the top of the base, gas mixers seated in the openings 90 in the bottoms of said grooves, burners upon the pipes and positioned below and adjacent to said mixers, and heat deflectors fastened to said pipes and positioned over the mixers.

In testimony whereof we hereunto affix 95 our signatures in presence of two witnesses.

JOHN C. WINANS.
HARRY KELLEY.
